Primary Examiner — Paula Greene(74) *Attorney, Agent, or Firm* — Clement Cheng(57) **CLAIM**

The ornamental design for wireless adapter, as shown and described.

DESCRIPTION

FIG. 1 is a perspective view.

FIG. 2 is a top face view.

FIG. 3 is a bottom face view.

FIG. 4 is bottom view.

FIG. 5 is a top view.

FIG. 6 is a right side view; and,

FIG. 7 is a left side view.

The dotted line in the drawing forms no part of the claimed invention.

1 Claim, 3 Drawing Sheets(56)
